UNITED STATES PATENT OFFICE

JOHN H. BASINGER, OF OKLAHOMA CITY, OKLAHOMA

DOOR BUFFER AND HOLDER

Application filed March 18, 1927. Serial No. 176,528.

This invention relates to means for controlling open doors, to protect the door from contact with the wall and to prevent slamming or accidental closing of the door; and the objects of the invention are; first, to provide an open-door latch or holder which engages the knob of the door and holds the door open; second, to provide a stop at the wall behind the door in position to intercept the knob of the opening door, the stop having a permanent back stop and a spring supported buffer which yields to the pressure of the door knob and absorbs or mitigates the shock when the door is thrown back with force; and, third, to provide a combination of the latch or holder with the stop whereby the holder is actuated to engage the door knob when the knob bears upon the buffer, and whereby the holder may be put out of operative relation to the buffer when the use of the holder is not required.

These objects are attained by the mechanism illustrated in the accompanying drawing, in which:

Fig. 1 is a side view of the holder in combination with the stop. Section is made thru the wall plate and the housing on the line 1—1 in Fig. 2. A door knob is in touch with the buffer without actuating the latch; Fig. 2 is a face view of a wall plate on which all the parts of the combination are supported, the buffer being removed to show the position of the crank by which the holder is actuated; Fig. 3 is a view from below upward, section being made thru the wall plate, on the line 3—3 in Fig. 1, showing the relation of the parts after the latch has been actuated to engage the door knob; Fig. 4 shows the buffer, removed from the combination, secured to a sweep or guide which maintains the buffer central with the opening in the wall plate; Fig. 5 shows a spring based on the wall plate and tensioned upward against a flattened portion of a crank shaft supporting the holder in position. Fragmentary section is made on the line 5—5 in Fig. 2; Fig. 6 is a pictorial view of a completed structure wherein the latch or holder is hinged to the wall plate below the buffer.

Similar numerals refer to similar parts thruout the several views.

A wall plate 1 is secured to the wall of the house and supports all the parts of the combination of the holder or latch and the stop. A box or housing 2 is secured to the wall plate 1 by rivets or screws and forms a chamber 3. At the narrow end of the chamber is pivoted a sweep 4 which is held in position by pins 5 passing thru the walls of the chamber and thru the corners of the sweep. A buffer 8 is secured to the sweep by screws or other means and stands centrally thru an orifice 9 in the wall plate 1. A spring 16 is based on the back wall of the chamber 3 and supports the sweep strongly forward against the wall plate 1. The buffer is positioned to intercept the knob of the opening door and protect the door and the wall from mutual contact, and when the door is opened back against the buffer with much force the spring is compressed and the buffer yields to the impact and prevents or mitigates the shock. The buffer is faced with soft rubber to avoid defacing the door knob and contributes to the prevention of shock. When the spring is compressed and the buffer is driven back into the chamber 3 by the door knob the back wall of the chamber becomes the permanent stop for the door.

The latch or holder 11 has a crank shaft 12 by which it is hinged to the wall plate 1 thru bearings 13. A crank 14, at the middle of the shaft, by which the holder is actuated stands across the lower part of the opening 9 in the wall plate and thru a tunnel 15 in the buffer 8. Normally the holder stands upward against the wall plate and the crank stands downward and forward at an angle a little less than forty five degrees from the wall plate and well up against the roof of the tunnel 15 in the buffer 8. When the buffer is driven back into the chamber 3 by the door knob 16 the roof of the tunnel bears on the crank 14 and turns it backward, with a little downward swing, thru nearly a quarter of a circle and moves the holder forward and downward over the door knob, along the course of the broken line from *a* to *b* in Fig. 1, till it rests on the stem 17 of the door knob 16. The latch is hinged to the

wall plate on a line below the center of the buffer and below the center of the door knob so that the holder will not slide up over the curved surface of the upper half of the knob when traction is made against the holder. 5 The crank may be entirely below the buffer (shown in Fig. 6) and some means other than the tunnel provided to connect it with the buffer or with the sweep 4.

10 Springs 18 based on the wall plate 1 and tensioned upward against a flattened portion of the shaft 12 holds the latch in normal position.

The door knob may be put in touch with 15 the buffer without depressing it and the holder actuated by hand to engage the door knob independent of the buffer. When the door is to be released the holder is lifted by hand to its normal position.

20 At times when the use of the holder is not required it may be turned downward against the wall plate, in the position indicated by the broken line *d d*. In that position it is not actuated by the buffer and does not interfere with its use as a door stop.

25 Aside from its combination with the door stop, a holder at the door knob so easily manipulated by hand to hold and release the door affords a convenience that may not be 30 found in door holders at the floor or on the bottom of the door or the base of the wall. A door stop encountering the door knob presents resistance to the violently opened door nearer its middle and in some measure balances the strain on the door. This combination put no incumbrance on the door and no obstruction on the floor or the base of the wall, and in its position at the door knob it stands out but little from the wall in contrast to the outstanding stop that encounters 40 the body of the door. The structure may be made ornamental, or it may be made inconspicuous by resemblance to electric wall switches and outlets.

45 I claim in a door control:

1. A door holder adapted to engage the knob of an open door and hold the door in open-door position, a crank connected with the said door holder by which the holder is 50 actuated, a buffer which is actuated by the knob of an open door and which actuates the said crank and thereby actuates the said door holder to engage the said door knob, a fixed stop which supports the said buffer when it is actuated.

2. A door holder adapted to engage the knob of a door and hold the door in open position, a crank connected with the said door holder by which the holder is actuated, 60 a buffer which intercepts and is actuated by the said knob when the door is opened and which actuates the said crank and thereby actuates the said door holder to engage the knob of the door when the knob actuates the 65 buffer.

3. A device of the class described comprising a buffer adapted to be engaged by a door and cushion the opening of the same, a pivotally mounted door holder adapted to engage the door knob and hold the door open, 70 said door holder being movable toward operative position by said buffer.

4. A device of the class described comprising a fixed support, a holder for engagement with a door knob pivotally connected with 75 said support, a yieldable buffer for engagement by the door, and means connecting said holder and buffer to cause the holder to engage the door knob.

Signed this 4th day of March, 1927.

JOHN H. BASINGER.
